HASP FOR PADLOCKS

Edward D. Livenick, Chicago, Ill.

Application November 20, 1942, Serial No. 466,311

1 Claim. (Cl. 292—281)

My invention relates to improvements in hasps for padlocks, the principal object in view being to equip such hasps inexpensively with efficient, simply constructed and easily applied means for opening the same out flat against surfaces to which they may be attached, and as soon as the hasps are released from the adjunctive staple members.

Other and subordinate objects are also comprehended by my invention, all of which, together with the precise nature of my improvements, and the advantages thereof, will be readily understood when the succeeding description and claim are read with reference to the drawing accompanying and forming part of this specification.

In said drawing:

Figure 1 is a fragmentary view in front elevation illustrating a hasp equipped according to my invention and shown in opened position.

Figure 2 is a view in horizontal section taken on the line 2—2 of Figure 1, and

Figure 3 is a view in front elevation illustrating the hasp closed over the staple member and padlocked.

Referring to the drawing by numerals, my improvements have been illustrated therein as embodied in a hasp 1, of usual construction with exceptions presently noted, and comprising an anchoring plate 2 shown secured to a door 3 by screws 4 and having at the inner end thereof a hinge barrel 5 straddled by a divided hinge barrel 6 on the inner end of a latch plate 8 swingable about the axis of the barrels 5, 6 over the plate 2 and over the usual staple member 9 on the door frame 10 to project the staple through an end slot 11 in the plate 8 for the attachment of a padlock 12 to said staple member.

According to my invention, a rectangular notch 13 is provided in the hinge barrel end of the latch plate 8 between the parts of the divided barrel 6. The pintle 14 extends at its opposite ends beyond the parts of the hinge barrel 6 and has its terminals upbent, as at 15, against a pair of end washers 16 on the pintle 14. A one-piece, resilient wire spring is provided including a pair of coils 17 surrounding the opposite ends of the pintle 14, respectively, between the washers 16 and the parts of the divided barrel 6, a straight section 18 connecting the inner ends of the coils 17 and overlying the anchoring plate 2 adjacent the barrels 5, 6, and a pair of sec-

tions 19 forming extensions of the outer ends of the coils 17 and extended oppositely, relatively, across the inner face of the latch plate 8 through the notch 13 with their terminals lying against the outer face of said latch plate 8. As will be apparent, the coils 17 and sections 19 react against the inner face of the latch plate 8 to yieldingly swing said latch plate open flat against the door 3, when said latch plate is released from the staple member 9, the coils 17 being wound to uncoil in the direction of opening movement of the latch plate 8, and held against uncoiling in the opposite direction by the section 18 bearing against the anchoring plate 2.

A particular advantage of my invention is that uncontrolled swinging of the latch bar, frequently resulting in injury to an operator and damage to the hasp, is positively obviated, also rattling of doors due to play of the hasp on the staple member against the padlock.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claim.

What I claim is:

30. A hasp comprising an anchoring plate, and a latch plate, a hinge connecting said plates for swinging of the latch plate into and from overlying relation to the anchoring plate and including a hinge barrel and a hinge pintle having headed ends extending out of the ends of the hinge barrel, and a spring member for urging said latch plate away from such overlying relation comprising a pair of coils circumposed on said extending ends of said pintle, respectively,

35. a straight section connecting the coils at inner ends thereof and bearing against one side of the anchoring plate, said latch plate having an opening therein adjacent said barrel, and said spring having a pair of straight sections forming extensions of the other ends of said coils and extending oppositely across the latch plate in crossed relation through said opening in overlapping relation to the sides of the opening whereby said ends are slidably interlocked with said latch plate.

40. A hasp comprising an anchoring plate, and a latch plate, a hinge connecting said plates for swinging of the latch plate into and from overlying relation to the anchoring plate and including a hinge barrel and a hinge pintle having headed ends extending out of the ends of the hinge barrel, and a spring member for urging said latch plate away from such overlying relation comprising a pair of coils circumposed on said extending ends of said pintle, respectively,

45. a straight section connecting the coils at inner ends thereof and bearing against one side of the anchoring plate, said latch plate having an opening therein adjacent said barrel, and said spring having a pair of straight sections forming extensions of the other ends of said coils and extending oppositely across the latch plate in crossed relation through said opening in overlapping relation to the sides of the opening whereby said ends are slidably interlocked with said latch plate.

EDWARD D. LIVENICK.
